DESIGN FOR AN ENSEMBLE GARMENT

Dorothy E. Berger, Newark, N. J., assignor to Apolda Knitting Mills, New York, N. Y., a Copartnership consisting of Louis C. Schnitzler and George R. Schnitzler

Application June 29, 1933. Serial No. 48,594

Term of patent 3½ years

To all whom it may concern:

Be it known that I, DOROTHY E. BERGER, a citizen of the United States, and a resident of Newark, in the county of Essex and State of New Jersey, have invented a new, original, and ornamental Design for an Ensemble Garment, of which the following is a specification, reference being had to the accompanying drawing forming a part thereof, in which:

Fig. 1 is a front elevational view of the ensemble garment;

Fig. 2 is a rear view of the coat section of the garment disclosed in Fig. 1;

Fig. 3 is a rear view of the trousers portion of the garment shown in Fig. 1; and

Fig. 4 is a front elevational view of the upper part thereof with certain parts of the garment shown in a different position.

I claim:

The ornamental design for an ensemble garment, substantially as shown and described.

DOROTHY E. BERGER.
